UNITED STATES PATENT OFFICE

ALBERT F. THOMPSON, OF ADEL, IOWA.

DESIGN FOR A BADGE.

SPECIFICATION forming part of Design No. 27,419, dated July 27, 1897.

Application filed July 30, 1896. Serial No. 601,121. Term of patent 14 years.

To all whom it may concern:

Be it known that I, ALBERT F. THOMPSON, a citizen of the United States of America, and a resident of Adel, in the county of Dallas and State of Iowa, have invented a new and useful Design for a Campaign Badge, of which the following is a specification.

The leading feature of my design is a conventionalized image of an elephant having a medallion in its side, the image being in bas-relief and the medallion in alto-rilievo.

In the drawings, Figure 1 is a view in elevation, illustrating the face of my design. Fig. 2 is a sectional elevation of my design on the indicated line 2 2 of Fig. 1.

In my design I employ the image of an elephant conventionalized by splitting the same

vertically and longitudinally and adding to the portion retained by me the two legs and the tusk; that would by an actual act of splitting be removed. In other words, I use a bas-relief image with four legs, a tail, two tusks, one ear, one eye, the trunk, and one-half of the body. In the side of the body portion of the image I form a circular medallion 10, which is concaved relative to the body portion or in alto-rilievo.

I claim as my invention—

The design for a campaign-badge, substantially as herein shown and described.

ALBERT F. THOMPSON.
